UNITED STATES PATENT OFFICE

132,311

DESIGN FOR A BRACELET LINK OR SIMILAR ARTICLE

Jack Dubinsky, Chicago, Ill.

Application March 7, 1942, Serial No. 106,111

Term of patent 7 years

To all whom it may concern:

Be it known that I, Jack Dubinsky, a citizen of the United States, residing at Chicago, in the county of Cook and State of Illinois, have invented a new, original, and ornamental Design for a Bracelet Link or Similar Article, of which the following is a specification, reference being had to the accompanying drawing, forming a part thereof, in which:

Fig. 1 is a front elevational view of a bracelet link or similar article, showing my new design, enlarged approximately four times its actual size; and

Fig. 2 is a top plan view thereof.

I claim:

The ornamental design for a bracelet link or similar article, as shown and described.

JACK DUBINSKY.
